UNITED STATES PATENT OFFICE.

FRANCIS HEAD, OF NEW YORK, N. Y.

DRYING APPARATUS.

Application filed January 7, 1926. Serial No. 79,758.

The invention relates to apparatus for drying coated or uncoated flexible materials of indefinite length, such, for example, as oil cloth, wall paper, etc.

According to present practice it is common to employ drying sticks upon which the material is supported in the form of loops, and to feed these sticks with the fabric supported thereon through a drying chamber. In order that the drying of the material shall keep pace with the printing, coating, or other prior operation on the material, it has been found expedient to decrease the longitudinal speed of the sticks and fabric through the drying chamber so that a great length of material may be accommodated, and devices for effecting such decrease in speed within the drying chamber have heretofore been employed. But in all prior devices of which I am aware, this has been accomplished with devices in which the drying sticks were not permanently attached to the chains or other flexible travelling means which served to move the sticks forwardly through the chamber. Where the sticks thus loosely engage the chains which move them forward they are liable to be displaced or fall from the chains with resulting damage to the material, which may be of serious consequence. In such an arrangement it is also necessary either to return them to the entrance end of the machine manually or by machinery of a complicated nature. By permanently attaching the sticks to the carrying chains, and devising means to give different speeds to the sticks at different points thereof, I am able to obviate the difficulties inherent in prior constructions while retaining the benefits derived from slow speed of the fabric through the drying chamber.

It is therefore the object of this invention to combine the advantages which flow from slow speed of the material through the drying chamber with those which flow from permanent attachment of the sticks to their carrying and moving means,

The invention consists in the novel mechanism hereinafter described and claimed. It may be embodied in different forms but the best form now known to me will be described, reference being had to the accompanying drawings illustrating the same.

In the annexed drawings:

Figure 1 is a diagrammatic view showing a vertical section through the drying chamber illustrating the folds of the ma-

terial to be dried and the endless stick carrying chain;

Fig. 2 is a longitudinal vertical section through the upper portion of a drying chamber, showing parts of the mechanism in detail;

Fig. 3 is a top plan view of one side thereof, illustrating the relation of the stick carrying and stick moving chains;

Fig. 4 is an enlarged view of a sprocket wheel, stick carrying chain, and chain stripper therefor, on line 4—4 of Fig. 3;

Fig. 5 is a cross section on line 5—5 of Fig. 3;

Fig. 6 is a front elevation of the chain stripper, showing its relation to the sprocket wheel and chain; and

Fig. 7 is a detail view showing the stick moving chain 12 provided with stick engaging lugs.

Referring to the drawings in detail, in which the same reference numeral is used throughout to designate the same part, a drying chamber 1, in which heated air is circulated in any suitable way, is provided at the entrance end with a slot 2, through which enters the material 3 (hereinafter called fabric) to be dried. The fabric passes over a guide 4, herein shown as a roll, suitably supported in the drying chamber, and successive points thereof are engaged by a plurality of sticks 5 fixed to a pair of endless chains 6, engaging sprocket wheels 7, 7' of the same size, at opposite ends of the chamber 1, by means of which the fabric is formed into loops 8 and carried slowly through the drying chamber by mechanism hereinafter to be described, from which it finally passes through a slot 9 at the exit end thereof, where it may be wound on a suitable receiving roll (not shown).

During the loop forming period at the entrance end of the drying chamber the sticks, in the embodiment now contemplated, are about 24 inches apart, from center to center, but by apparatus to be hereinafter described they are nested together so as to be about 8 inches apart, and while so nested they are passed slowly through the drying chamber, under the control of a pair of stick moving chains, to which they are transferred, arranged outside of the stick carrying chains at opposite sides of the chamber. By so nesting the drying sticks the loops 8 in the fabric are brought as close together as is practicable while preventing actual en-

gagement of one fold with another. At the folds near the exit end of the chamber, the sticks are separated to the initial distance and are moved at the initial speed. By this arrangement the fabric moves out of the drying chamber at the same speed as it enters, but it is moved slowly at an intermediate point, whereby the fabric has ample time to dry, and a large quantity of fabric may be accommodated. The mechanism for effecting these motions will now be described.

Shafts 10, 10' are suitably mounted in the drying chamber, shaft 10' being the driving shaft, driven by any suitable means (not shown), and from which is driven the shaft 10 at the entrance end by any suitable intermediate gearing. For this purpose, in the embodiment shown, I employ chains and sprocket wheels. Shaft 10' has fixed thereto at opposite ends, the sprocket wheels 7' (only one of which is shown), and shaft 10 has fixed thereto sprocket wheels 7 (only one of which is shown), which are engaged by the links of the endless stick carrying chains 6, guided at the opposite lower corners of the drying chamber by guides 11, 11' (Fig. 1). The sticks 5 are fixed to these chains by any suitable means, as indicated in Fig. 4, at such points that the outer ends 5' project a slight distance beyond the chains 6, as indicated in Fig. 5, over stick moving chains 12. The stick moving chains 12 are endless chains, the end loops or bights of which engage sprocket wheels 13, 13', rotatably mounted on fixed shafts 14, 14', inside of but near shafts 10, 10', respectively, so that the upper runs of the chains 12 will be in substantially the same plane as the stick-carrying chain 6, as indicated in Fig. 5. The stick-moving chains 12 are moved much more slowly than the stick-carrying chain 6, by any suitable gearing. Herein I have shown sprocket wheels and chains geared to the driving shaft 10'. Fixed to driving shaft 10' is a sprocket wheel 15, about one-third the diameter, in the embodiment shown, of the sprocket wheel 7'. A sprocket chain 16 is driven by the sprocket wheel 15, which in turn drives a sprocket wheel 17 fixed to a hub 18 rotating freely on the fixed shaft 14', ball bearings being preferably employed. Fixed to the same hub 18 is another sprocket wheel 13', above referred to, which is engaged by the stick moving chain 12. The opposite bight of the stick moving chain 12 engages sprocket wheel 13, of the same size as sprocket wheel 13'. Sprocket wheel 13 is fixed to a hub 19, to which is also fixed another sprocket wheel 20, of the same size as sprocket wheel 17, the hub 19 rotating freely on fixed shaft 14. A sprocket chain 21 engages sprocket wheel 20 and drives another sprocket wheel 22, of the

same size as sprocket wheel 15, fixed to a hub 23 secured to shaft 10, to which the sprocket wheel 7, engaged by the stick carrying chain 6, is also fixed. Another sprocket wheel 24 is also fixed to shaft 10, and drives a sprocket chain 25, which, in turn, drives a sprocket wheel 26, of the same size as sprocket wheel 24, fixed to a hub 27, rotating freely on fixed shaft 14. To the hub 27 is fixed a sprocket wheel 28, of the same size as sprocket wheels 7, 7', both of which are engaged by the links of the stick carrying chain 6. It will be observed that the gear ratio between the driving shaft 10' and the sprocket wheel 13', which gives motion to the stick-moving chains 12, is 3 to 1, whereby the speed of chains 12 is only one-third of the speed of the stick carrying chains 6 at the entrance and exit ends of the drying chamber. The gear ratio at the opposite end is, of course, made to accord, so as to move the stick carrying chains 6 at the same speed at the entrance and exit ends before and after the sticks are out of engagement with the low speed stick moving chains 12, which controls their motion through the central portion of the drying chamber, as hereinafter described.

As the sticks 5 are moved past the inner end loops or bights of the stick moving chains 12, the ends 5' thereof are engaged by the links of this chain, which thereafter controls the speed of forward motion of the sticks. The sticks may be carried along merely by frictional engagement thereof with the chains 12, or, if desired, chains 12 may be provided, at intervals, with projections 29, which positively engage the ends 5', as indicated in Fig. 7. The length of the stick carrying chains 6 between sprocket wheels 13' and 28, between which sprocket wheels the chain is slack, is such as to permit the chains 6 to be formed into a series of loops 30.

In the forward movement of the chains over sprocket wheels 28 the slack in the chain would permit its links to remain in engagement with the sprocket wheel. Ordinarily it would disengage itself therefrom, but to insure such disengagement strippers 31 are provided (see Figs. 4 and 6), which consist of members whose lower ends are suitably supported in the drying chamber and whose upper ends are slotted as indicated at 32, forming arms 33, 33' which straddle the teeth of the sprocket wheels 28, lying underneath the chain 6 and slightly inclined from a vertical plane. As the chains are carried into engagement with the strippers 31 the links are positively separated from the sprocket wheels.

Near the exit end of the drying chamber the low speed stick moving chains 12 lose control of the sticks, as the ends 5' of the sticks pass off the ends of these chains, and

are brought under control of the more rapidly moving stick carrying chains 6. At this point the loops 30 in the chains are taken up, and to assist in smoothly and surely straightening out the chains 6, I provide 5 guard members 34, against which the forward portions of the loops successively engage, and over which the chains are drawn in the straightening movement.

10 Near the exit and entrance ends, the chains 6 are supported by suitable guides 35, 35' (Figs. 2 and 3), suitably fixed to the framework of the drying chamber, and the upper and lower runs of chains 12 are supported by similar guides 36, 37. In order to 15 keep the sticks from sidewise movement, an L-beam 38 (Figs. 3 and 5) is employed, the base 39 of which rests upon the framework of the drying chamber, and a side 40 of 20 which extends upwardly alongside the ends 5' of the sticks 5.

Operation: The flexible material 3 to be dried passes over guide 4 and then downwardly across the path of the sticks 5 which 25 are continuously moving in the direction indicated by the arrow in Fig. 3. As a stick which has engaged a portion of the fabric nears the point of transfer of the sticks on to the slowly moving chains 12, the weight of 30 the fabric between the guide 4 and the moving stick 5 causes it to drop back of the onwardly moving stick to form a succeeding loop therein, and so on indefinitely during the operation of the machine. As the ends 35 5' of the sticks 5 pass beyond the inner end loop or bights of the chains 12 the slack in chains 6 permit such ends 5' to drop onto the chains 12 by which they are thereafter carried along toward the exit end of the chamber. 40 In the embodiment shown the chains 12 move at only one-third the initial speed of chains 6, consequently a stick which has been transferred to the control of chains 12 will have moved but one-third of the distance 45 which the stick moved while under the control of the stick-carrying chains 6 during the same time interval, from which it follows that the sticks will be nested on the stick-moving chains 12; by which they are slowly moved through the drying chamber, in this 50 nested relation, toward the exit end. As the sticks pass out of control of the slowly moving chains 12 they are again brought under the control of the more rapidly moving stick-carrying chains 6, through which the loops incidentally formed in the chains by 55 the nesting of the sticks is drawn out, and the speed of the fabric is increased to its initial speed, whereby the fabric is fed out of the drying chamber at the same speed as it is fed into it. Thereafter the fabric is handled in the way known to the art.

60 It will be apparent from the above description that I have devised an apparatus 65 which will effectively attain the objects

above indicated, wherein the sticks are permanently attached to their carrying means, thus securing certainty in their functioning at all times and avoiding damage to the material, wherein complicated mechanism for returning the sticks to initial position is dispensed with, while retaining the known feature of nesting the sticks at an intermediate portion of their travel through the drying chamber and moving them slowly there-through.

While I have described a specific embodiment of the invention, it is obvious that the various features thereof may be modified. For example, other gearing may be employed for giving different speeds to the ends and intermediate portion of the stick-carrying chains, and many other changes may be made without departing from the principles herein disclosed. It is therefore to be understood that the invention is not confined to the details described but that it includes all structures comprehended within the terms of the appended claims.

I claim:

1. In a drying apparatus, in combination, a drying chamber; an endless, flexible stick carrier; drying sticks fixed thereto; means for giving a continuous travelling motion to the carrier; and means for nesting the sticks in an intermediate portion of the stick carrier and for moving them continuously at a slow speed while so nested.

2. In drying apparatus, in combination, a drying chamber; an endless, flexible stick carrier; drying sticks fixed thereto; means for giving a continuous travelling motion to the carrier; means for giving the sticks a slow motion during their passage through an intermediate portion of the drying chamber comprising a stick moving member arranged alongside the flexible carrier and provided with means to move it at less speed than the carrier; and means to transfer control of the sticks from the stick carrier to the stick moving member.

3. The combination specified in claim 2 in which there are means for forming the carrier into loops at the point of transfer of the sticks.

4. The combination specified in claim 2 in which the means to transfer control of the sticks from the stick carrier to the stick moving member consists of a sprocket wheel engaged by the stick carrier and a stripper to strip the carrier therefrom.

5. The combination specified in claim 2 in which the stick carrier consists of chains and sprocket wheels to drive the same with additional means to strip the chains from the sprocket wheels to form loops therein at the time of their transfer.

6. In drying apparatus, in combination, a drying chamber; parallel endless stick-carrying chains; drying sticks fixed thereto;

- sprocket wheels at opposite ends of the chamber engaged by the chains; intermediate sprocket wheels near the entrance end of the chamber also engaged by the stick-carrying chains; a set of endless stick-moving chains outside of the stick-carrying chains and in substantially the same horizontal plane and having end loops or bights terminating short of the ends of the upper 10 runs of the stick-carrying chains and over which stick-moving chains the ends of the sticks extend; and means to move the stick-moving chains in the same direction as the stick-carrying chains but at less speed.
- 15 7. The combination specified in claim 6 with means to form loops in the stick-carrying chains at the point of transfer of control of the sticks to the more slowly moving chains.
- 20 8. The combination specified in claim 6 with means to form loops in the stick-carrying chains at the point of transfer of control of the sticks to the more slowly moving chains, and with a chain guard at the opposite end of the drying chamber to insure the 25 elimination of such loops.
9. In drying apparatus, in combination,

a drying chamber to which material to be dried is admitted at one end and withdrawn at the other; a pair of endless, flexible, stick-carrying chains; like sprocket wheels at opposite ends of the chamber over which the stick-carrying chains pass; stick-moving chains arranged outside of, and in the same horizontal plane as, the stick-carrying chains, and having their end loops inside said sprocket wheels; drying sticks fixed to the stick-carrying chains having their outer ends extending over the stick-moving chains to be engaged and moved thereby; like sprocket wheels engaging the end loops of the stick-moving chains; means to rotate the sprocket wheels of the stick-carrying chains at the same speed; and means to rotate the sprocket wheels of the stick-moving chains but at such speed that the stick-moving chains, which control the rate of movement of the sticks at an intermediate portion of their transit through the drying chamber, is much less than that of the stick carrying chains at opposite ends of the chamber.

In testimony whereof I affix my signature.

FRANCIS HEAD.
